ARM MUSCLE EXERCISING APPARATUS

Glenn M. Ricketts, Rte. 1, Belle Center, Ohio 43310

Filed Oct. 24, 1973, Ser. No. 409,131

Term of patent 14 years

Int. Cl. D21—01

U.S. Cl. D34—5 K

FIG. 1

FIG. 1 is a top plan view of an arm muscle exercising apparatus showing my new design;

FIG. 2 is a side elevational view thereof;

FIG. 3 is a vertical sectional view taken along line 3-3 of FIG. 1.

FIG. 4 is a vertical sectional view taken along line 4-4 of FIG. 3.

The coiled spring member shown partially in full line is continuous throughout as indicated by broken lines in FIGS. 1, 2 and 3.

I claim:

The ornamental design for an arm muscle exercising apparatus, substantially as shown and described.
